ELECTRICAL CONNECTOR SOCKET

James M. Fetherolf, White Plains, Gerard E. Forrest, Beechhurst, and Francis W. See, Bronx, N. Y., assignors to The Sperry Corporation, a corporation of Delaware

Application September 13, 1945, Serial No. 616,102

8 Claims. (Cl. 174—18)

1

The present invention relates to electrical connector devices, and particularly to sockets for receiving electron discharge devices or multiple circuit electrical connectors.

Where very high voltages are involved in radio and electronic apparatus, it is often necessary to provide high voltage insulation between electrical conductors, and particularly to provide very high voltage insulation between a grounded metal chassis, used for supporting the circuit components and the terminals and wiring associated with the components. A compact arrangement of the circuit components and of the conducting wires may be insulated for operation at very high voltage and for use in rarefied atmospheres by the provision of an oil-filled chassis, wherein all wired and exposed conductive elements are immersed in the insulating oil. Alternatively, the chassis may be filled by a dry gas maintained at a high pressure. Ordinary multicircuit electrical connector sockets, such as sockets commercially available for electron discharge tubes, are not suitable for use in oil-filled or pressurized gas-filled chassis applications. The present invention is concerned with the provision of a socket suited for such an arrangement.

An object of the present invention is to provide an easily manufactured, inexpensive and compact connector socket or device capable of withstanding very high voltages and suited for providing a fluid-tight seal.

The invention in another of its aspects relates to novel features of the instrumentalities described herein for achieving the principal object of the invention and to novel principles employed in those instrumentalities, whether or not these features and principles are used for the said principal object or in the said field.

A further object of the invention is to provide improved apparatus and instrumentalities embodying novel features and principles, adapted for use in realizing the above objects and also adapted for use in other fields.

In accordance with the present invention, a vitreous cup, e. g. a glass cup, is provided with a plurality of connector elements or contact members which may be arranged to receive cooperating contact elements such as the metal prongs of an electron discharge tube. These contact members may be hermetically sealed into the bottom of the vitreous cup, and may be arranged so that their contact pin receiving ends are recessed well within the vitreous cup.

A metallic band surrounding the vitreous cup is plastically bonded thereto and is adapted to be

2

bonded to an opening in a metal supporting member or wall, e. g. a circular opening through a metal chassis. The contact members are so positioned within the cup, and the metallic mounting band is so arranged externally of the cup, that the paths of electric voltage strain along the surfaces of the vitreous cup are made very long, the path in air from the pin receiving ends of the contact members along the inside wall of the cup, over the top of the cup, and down the outer wall of the cup to the mounting band being made particularly long.

An embodiment of the present invention is illustrated in the drawing, wherein:

15 Fig. 1 is a perspective view of a socket constructed in accordance with the present invention;

Fig. 2 is a longitudinal cross-sectional view of the socket; and

20 Fig. 3 is an elevation, partly in section, showing a socket in accordance with the present invention incorporated within an oil-filled chassis assembly and supporting an electron discharge tube.

25 Like reference characters are used throughout the figures to designate corresponding parts thereof.

Referring now to Fig. 1, there is shown a socket 11 constructed in accordance with the present invention and including a vitreous cup 12 surrounded by a metallic mounting band 13. Within the vitreous cup there is a connector sub-assembly including a plurality of metallic contact members 14 arranged substantially parallel to the axis of the cup 12 and fixedly spaced at their upper ends by an insulating web 15. The contact members 14 extend through the bottom of the vitreous cup 12 and are hermetically sealed thereto. At their lower ends, the contact members 14 are arranged to receive the ends of conductor wires; while at their upper ends, the contact members 14 are arranged to receive the metal prongs of an electron discharge tube, or of a connector device arranged according to the base plan of an electron discharge tube.

40 The vitreous cup 12 preferably is of a hard glass material, such as Pyrex or Tronex, capable of withstanding rapid temperature changes and also capable of withstanding severe mechanical shocks.

45 The mounting band 13 is formed on the outer surface of the cup 12 by the "Metaplast" process, which involves etching and metallizing the surface of the cup 12 to which the metal band 13 is to be bonded, electroplating the etched sur-

face with a metal such as silver, and coating the silver band with tin by hot tin dipping or tin plating the band 13. The tinned mounting band 13 formed on the surface of cup 12 in the manner described above is hermetically sealed to the surface of the cup 12, so that when the outer surface of the band 13 is soldered into a suitable opening in a metal wall or chassis, no escape of fluid will be permitted between the cup 12 and the wall in which it is mounted.

The cup 12 preferably is molded in such a way that a key-pin guiding groove 16 is formed along its inner surface, and a plurality of substantially cylindrical openings through the bottom of the cup are provided for receiving the contact members 14. Preferably, also, a boss is formed on the outer surface of the cup 12 at the bottom of each of these cylindrical openings. The bottoms of the bosses are flattened by grinding, and the substantially radial surfaces thus formed are subjected to the "Metaplast" process, so that a tinned radial surface is provided at the bottom of each of these bosses. Each of the contact members 14 includes a rod-like lower portion 17 for installation within an opening through the bottom of the cup 12. The rod-like lower portion 17 of the contact members 14 may be slotted as at 18 to facilitate the connection of the circuit wires thereto.

The outer surfaces of the rod-like extensions 17 of contact members 14 are tinned. Tinned metal washers 19, having an inner diameter matched to the outer diameter of the contact member extensions 17 and having an outer diameter determined by the diameter of the ground radial surfaces of the bosses on the bottom of cup 12, are provided for cooperation with the contact members and with the plated lower surfaces of the bosses. When the contact members and washers are assembled as illustrated in Fig. 2, the washers 19, the contact member extensions 17, and the metal radial surfaces bonded onto the bosses are united by a solder bond, providing mechanical rigidity of the assembly and hermetically sealing the bottom of the cup 12.

The contact members 14 may be provided at their upper ends with spring clips 21, 22, or they may be arranged in any other desired manner for receiving the cooperating pins of an electron discharge tube. If preferred, the contact members 14 could be made tubular at their upper ends, and could be longitudinally slotted so that the pins of an electron discharge tube could nest coaxially within the upper ends of the contact members 14.

It has been found desirable to provide an insulating web 15 which may be die-punched or formed by jig-drilling to receive the upper ends of contact members 14 and to support these members in such a way that assembly in the bottom of the cup 12 is facilitated. A subassembly comprising the web 15 and the contact members 14 is made up by riveting the upper ends of the contact members 14 into the web 15 as at 23, and the subassembly including the web and the contact members may then be lowered into place in the cup 12. The assembly of the socket 11 is thereafter completed by soldering the washers 19 to the rod-like extensions 17 of contact members 14 and to the plated radial surfaces of the bosses on the bottom of the cup 12. If the contact members 14 are provided with spring clips 21, 22 at their upper ends for contact with the tube base connector pins, further holes 20 are drilled through the web 15 in a plan conforming to the spacing

plan of the tube base connector pins. If desired, the upper surface of the web 15 may be grooved as illustrated at 24 (Fig. 1) to facilitate the location of the tube-base pins, or the upper ends of the pin-receiving holes 20 through the web may be chamfered for this purpose.

The contact members 14 may be provided with radial bosses 25 to facilitate the location of the members 14 during assembly, and to lend further 10 mechanical rigidity to the assembled structure.

The socket 11 is illustrated in Fig. 3 installed in an opening in a metal wall 26, such as the upper wall of a chassis. This wall 26, as illustrated, has been "dimpled" or deformed by suitable dies in such a manner as to provide a substantially cylindrical inner surface for receiving the metallic mounting band 13 of the socket 11. The inner surface of the dimpled opening is tinned and is soldered to the band 13, to complete the 20 hermetic seal and to provide a strong mechanical support for the socket 11. If preferred, a flanged mounting ring may be employed upon the surface of the chassis for the junction with the mounting band 13, so that no deformation of the 25 chassis wall is required. The chassis in which the socket 11 is mounted is filled with oil 27, which serves not only for increasing the breakdown voltage capacity of the circuits associated with the socket 11, but also for receiving the heat transmitted through the contact members 14 from the cooperating contact pins of an electron discharge tube.

If desired, a rubber cap 28 or an elastic gasket 35 may be provided for deterring moist atmosphere from reducing the breakdown voltage capacity between contact members within the vitreous cup 12.

Because of the oil immersion of the external part of the socket 11 extending beneath the wall 26, the voltage required for a flash-over in oil 40 between the socket terminals and the chassis or wall 26 is made so great that a voltage breakdown over this path is extremely unlikely. Accordingly, barring a voltage breakdown through the cylindrical wall of the vitreous cup 12, the path over 45 which a voltage breakdown normally would occur is along the outer surface of the cup 12 from the upper edge of the band 13, over the top of the cup, and down its inner surface to the upper ends of the contact members 14. This path may be relatively long and, if desired, corrugations or barriers 50 may be formed on the surface of the cup 12 to further increase the voltage which the socket 11 is capable of withstanding. If desired, furthermore, a plurality of metallic bands obviously 55 may be formed around the inner or outer surfaces of the cup 12 for producing any desired potential distribution.

By virtue of the novel construction of the 60 socket in accordance with the present invention, compactness and economy of manufacture are achieved, and high voltage protection is provided in a leak-proof socket of a type affording rapid heat transfer into the heat-receiving and insulating immersion oil.

Where glass or other transparent material is used for the vitreous cup 12, moreover, the innermost parts of the socket are subject to visual inspection, so that any defects thereof may be 70 noted without resorting to special testing apparatus.

Since many changes could be made in the above construction and many apparently widely different embodiments of this invention could be made 75 without departing from the scope thereof, it is

intended that all matter contained in the above description or shown in the accompanying drawing shall be interpreted as illustrative and not in a limiting sense.

What is claimed is:

1. A recessed electrical connector socket for installation in an opening through a metal wall and for providing a fluid-tight boundary at said metal wall, comprising a vitreous cup, a metallic band bonded to the outer surface of said cup and providing a metallic outer surface to be plastically bonded to said metal wall both for mechanically supporting said cup and for preventing fluid flow between said wall and the outer surface of said cup, and at least one electric contact member passing through said cup and sealed into said cup, one end of said contact member being within said cup and being adapted to provide pressure engagement with a cooperating contact element, and the other end of said contact member being external of said cup and being adapted to be permanently connected to an electric circuit.

2. A recessed electrical connector socket for installation in an opening through a metal supporting member and for providing a fluid-tight boundary at said metal supporting member, comprising a glass cup, a metal band electroplated upon the outer surface of said cup and providing a metallic outer surface to be soldered to said supporting member both for mechanically supporting said cup and for preventing fluid flow between said supporting member and the outer surface of said cup, and at least one electric contact member passing through the bottom of said cup and sealed into said cup, one end of said contact member being adapted to engage a cooperating contact element and the other end of said contact member being adapted to be permanently connected to an electric circuit.

3. An electrical connector socket for installation in an opening through a metal supporting member and for providing a fluid-tight boundary at said metal supporting member, comprising a vitreous body, a metallic band bonded to the outer surface of said vitreous body and providing a metallic outer surface adapted to be soldered to said metal supporting member both for mechanically supporting said body and for preventing fluid flow between said supporting member and the outer surface of said body, and a plurality of electric contact members passing through said body and sealed into said body, one end of each of said contact members being adapted to provide pressure engagement with a cooperating contact element of a plug-in device, and the other end of each of said contact members being adapted to be permanently connected to an electric circuit.

4. An electrical connector socket for installation in an opening through a metal supporting member and for providing a fluid-tight boundary at said supporting member, comprising a vitreous body, a metallic band bonded to the outer surface of said body and providing a metallic outer surface adapted to be soldered to said supporting member both for mechanically supporting said body and for preventing fluid flow between said supporting member and the outer surface of said body, a plurality of electric contact members passing through said body and sealed into said body, one end of each of said contact members being adapted to engage a cooperating contact element of a multiple contact element electric device and the other end of each of said

contact members being adapted to be permanently connected to an electric circuit, and an insulating web mechanically interconnecting the contact-element engaging ends of said contact members for providing mechanical reinforcement and alignment thereof.

5. An electron tube socket for installation in an opening through a metal supporting member, providing a fluid-tight boundary at said supporting member and affording electron tube cooling by heat conduction through metal terminal members to a heat-receiving dielectric fluid, comprising a vitreous cup having an inside depth comparable with the depth of an electron tube base, a metallic band bonded to the outer surface of said cup and providing a metallic outer surface to be bonded to said supporting member both for mechanically supporting said cup and for preventing fluid flow between said supporting member and the outer surface of said cup, a plurality of electric contact members passing through said cup and sealed into fluid-tight contact with the surface thereof, each of said contact members having one end within said cup arranged for engaging a contact prong of an electron tube base, and the opposite end of each of said contact members being arranged externally of said cup to be permanently connected to an electric circuit and to be immersed in a heat-receiving dielectric fluid.

6. An electron tube socket comprising a vitreous cup having an inside depth comparable with the depth of an electron tube base, a plurality of electric contact members passing through the bottom of said cup and hermetically sealed thereto, each of said contact members having one end within said cup arranged for receiving a contact prong of an electron tube base, and the opposite end of each of said contact members being arranged externally of said cup to be permanently connected to an electric circuit and to be immersed in a heat-receiving and electric voltage breakdown preventing dielectric fluid.

7. An electron tube socket comprising a vitreous cup, a plurality of electric contact members passing through a wall of said cup and hermetically sealed thereto, each of said contact members having one end within said cup arranged for receiving a contact prong of an electron tube base, the opposite end of each of said contact members being arranged externally of said cup to be permanently connected to an electric circuit and to be immersed in a heat-receiving and voltage breakdown preventing dielectric fluid, and an insulating web within said cup mechanically interconnecting the contact-prong engaging ends of said contact members for providing mechanical reinforcement and alignment thereof.

8. An electron tube socket for installation in an opening through a metal supporting member, providing a fluid-tight boundary at said supporting member and affording electron tube cooling by heat conduction through metal terminals to a cooling dielectric immersion fluid, comprising a vitreous cup for receiving the base of an electron tube, a metallic band bonded to the outer surface of said cup and providing a metallic outer surface to be bonded to said supporting member both for mechanically supporting said cup and for preventing fluid flow between said supporting member and the outer surface of said cup, a plurality of electric contact members passing through the bottom of said cup and hermetically sealed thereto, each of said contact members having one end within said cup arranged for en-

gaging a contact prong of an electron tube base and the opposite end external of said cup arranged to be connected to an electric circuit and to be immersed in dielectric fluid, and an insulating web within said cup mechanically interconnecting the ends of said contact members for providing mechanical reinforcements and alignment thereof.
